UNITED STATES PATENT OFFICE.

FREDERICK GRINNELL, OF PROVIDENCE, RHODE ISLAND.

AUTOMATIC FIRE-EXTINGUISHER.

SPECIFICATION forming part of Letters Patent No. 269,203, dated December 19, 1882.

Application filed February 20, 1882. (No model.)

To all whom it may concern:

Be it known that I, FREDERICK GRINNELL, of the city and county of Providence, and State of Rhode Island, have invented a new and useful Improvement in Automatic Fire-Extinguishers; and I hereby declare that the following is a full, clear, and exact description of the same, reference being had to the accompanying drawings, forming part of this specification.

This invention is an improvement on Letters Patent No. 248,828, granted to me October 25, 1881, for an improvement in automatic fire-extinguishers, in which the outlet is secured to a flexible diaphragm, and is held tight against the valve by the internal pressure acting on the flexible diaphragm.

The invention consists in providing the case with a sliding piston, in which the valve-seat is formed, as will be more fully set forth hereinafter.

Figure 1 is a view of one form of automatic fire-extinguisher to which my present improvement is applied. Fig. 2 is a sectional view of the same, showing the piston provided with an outlet and valve-seat, held against a deflector, which also forms the valve, by the internal pressure. Fig. 3 is a top view of the automatic fire-extinguisher, showing the deflector perforated outside the central space which forms the valve by which the outlet is closed. Fig. 4 is a sectional view of an automatic fire-extinguisher in which a valve is held by securing the valve-stem in a rose or perforated sprinkler with fusible solder, or, as is indicated in broken lines, by a cap extending over the distributor and secured near its base by fusible solder. Fig. 5 is a sectional view of an automatic fire-extinguisher, showing a deflector held in place by means of compound levers and a piston provided with an outlet forced against the deflector by internal pressure. Fig. 6 is a view showing the extinguisher shown in Fig. 5 as it is when in operation, the deflector being suspended below the outlet.

The means shown in Fig. 5 for holding the deflector form no part of this present invention, but form the subject-matter of another application of even date herewith.

In the drawings, *a* is the inlet of the automatic fire-extinguisher, provided with a screw-

thread, by which it is secured in any suitable pipe-fitting.

b is an enlarged chamber, in which the piston *c* is placed with the flange *c'*, fitting the chamber water-tight, or constructed so as to be self-packing.

b' is a projection or lip, by which the motion of the piston *c* is limited and prevented from being forced out of the chamber *b*. The piston *c* is provided with the central outlet, *d*, the rim of which forms the valve-seat.

e is the valve, which in Figs. 1, 2, 3, 5, and 6 is the central part of a deflector-disk, but in Fig. 4 is an ordinary valve. The valve is held in a fixed position either by securing the stem in a frame or distributor by means of fusible solder or by other means, which by the action of heat will release the valve and allow it to move outward sufficiently to discharge the water.

The action of the device is as follows: When the valve is secured in the proper position, the extinguisher secured to a system of pipes, and the water or other fire-extinguishing fluid is let on, the pressure of the water, acting on the large area of the piston *c*, between the central outlet and the flange *c'*, forces the rim of the outlet firmly against the valve, and no matter what the change in pressure or the water-hammer, the joint will always remain tight.

A spiral spring is shown in Fig. 4 to hold the piston to the valve, and such a spring may be used in all the devices to insure a tight fit between the valve and outlet, assisted, however, by the pressure of the water on the piston. When, now, the heat rises to the point at which the solder by which the valve, or a valve forming part of a deflector, fuses, the pressure exerted by the piston *c* will break the soldered joint, and the water will force the valve away from the outlet, when the water will be discharged either against the deflector, and thus broken up and dispersed, or through the perforations of a distributor, to be spread over a large area on the fire, the office of the piston *c* being to maintain a tight joint under all pressures and to assist in breaking the joint when weakened by heat.

In place of the overhanging edge *b'* of the chamber *b*, any kind of stop may be used to prevent the piston *c* from being forced from the chamber.

Having thus described my invention, I claim as new and desire to secure by Letters Patent—

1. In an automatic fire-extinguisher, the combination, with a piston having a central outlet and adapted to yield to the pressure of the fluid confined by it, of means or devices, substantially as described, for keeping a valve closed against said outlet until the restraint which said means exerts against the opening

10 of the valve is removed by the action of heat.

2. The combination, substantially as before set forth, of the discharge-valve and a deflector attached to and moving with said valve, with the piston constructed to maintain a water-

15 tight joint between its outlet and the valve.

3. The combination, substantially as before set forth, of a piston capable of yielding to the pressure of the fluid, having a valve-seat surrounding its outlet, and a valve against which the valve-seat is forced by the fluid-pressure 20 on the piston, with means, substantially as described, for retaining the valve in place until released by the action of heat, as described.

FREDERICK GRINNELL.
